DESIGN FOR A COCKTAIL SHAKER

Philip Meshberg, Trumbull, Conn.

Application March 9, 1946, Serial No. 127,305

Term of patent 3½ years

(CL. D2—3)

To all whom it may concern:

Be it known that I, Philip Meshberg, a citizen of the United States, residing at Trumbull, county of Fairfield, and State of Connecticut, have invented a new, original, and ornamental Design for a Cocktail Shaker, of which the following is a specification, reference being had to the accompanying drawing, forming part thereof.

Figure 1 is a front elevation of a cocktail shaker showing my new design.

Fig. 2 is a front elevation of the top portion of the cocktail shaker rotated ninety degrees from the position shown in Fig. 1.

Fig. 3 is a bottom view of the cocktail shaker shown in Fig. 1.

Fig. 4 is a top view thereof.

The essential feature of the design resides in the configuration of the cover portion and spout of the cocktail shaker as shown.

I claim:

The ornamental design for a cocktail shaker, as shown and described.

PHILIP MESHBERG.
